UNITED STATES PATENT OFFICE

CORTIS F. SHERMAN, OF HARTFORD, CONNECTICUT

DIEING MACHINE

Application filed June 21, 1929. Serial No. 372,792.

My invention relates to the class of machines that are commonly employed for stamping, punching, dieing or other similar operations, and an object of my invention, among others, is the production of a machine of this class of simple construction, that will prevent undue wear upon the dies and that will be otherwise particularly efficient in operation.

10 One form of a machine embodying my invention and in the construction and use of which the objects herein set out, as well as others, may be attained, is illustrated in the accompanying drawings, in which—

15 Figure 1 is a view of my improved machine in front elevation, with parts broken away to show construction.

Figure 2 is a view in vertical section through the driving shaft on a plane denoted by the dotted line 2—2 of Figure 1, the machine frame being shown in side elevation and with parts broken away to show construction.

20 Figure 3 is a view in cross section on a plane denoted by the dotted line 3—3 of Figure 1.

Figure 4 is a view, partially in plan and partially in cross section, on a plane denoted by the dotted line 4—4 of Figure 1.

25 Figure 5 is a face view, scale reduced, of one of the side members of the sliding frame.

Figure 6 is a view, scale reduced, of the main or supporting frame of the machine.

30 My improved machine belongs to that type of presses in which the operating mechanism is located within the main supporting part of the frame and below the bed or table that carries the stationary die, and in which a reciprocating die or punch is carried by a head located above the table or bed and forming part of a sliding frame, said frame being operatively connected with the operating mechanism for reciprocating 35 movement thereby.

In the accompanying drawings the numeral 10 denotes the main or supporting frame of my improved machine having a broad base for stable support of said frame, and with a chamber 11 within the frame, a

table or bed 12 for support of a stationary die forming the top of said chamber. Vertically extended ribs 13 and 14 are oppositely arranged on the outer and inner sides of the side parts of the main frame, and as shown in Figure 3 of the drawings, and bearings are suitably formed within the sides thus thickened to receive a main or driving shaft 15 which is rotatably mounted in said bearings and which may be driven in any suitable manner, as by means of a driving pulley 16. This pulley is rotatably mounted on the shaft and is adapted to be intermittently connected therewith by means of a suitable clutch that may be of any well known construction and that may be operated in any well known manner, as will be readily understood by those skilled in the art, and for this reason a detailed illustration and description are omitted herein. A suggestion, however, of this clutch is shown in Figure 2 wherein a notch 17 in the main shaft receives a pawl 18 for connecting the pulley and shaft when desired. Openings are formed through the front and rear sides of the main frame for access to the mechanism therein, and wide slots 19 are oppositely formed in the side parts of the main frame for a purpose to be hereinafter described.

35 The upper or movable die is carried by a sliding frame comprising side members 20, a reciprocating head 21 and a tie beam 22. The side members are arranged to slide on the outer surfaces of the sides of the main frame, as upon ways 9 at opposite sides of said frame, and the tie beam 22 is secured at its ends, as by bolting or otherwise, to the inner sides of the sliding members, extending through the slots 19, said beam being of a length to space said side members a proper distance apart. The side members may be cut or slotted at their upper ends to form extensions 23, and studs 24 are formed at the ends of the extensions 23 to receive the head 21, in the construction herein shown said head having holes to receive the studs and the latter being threaded to receive nuts to secure the parts firmly together. The ways 9 afford extremely long 40

bearings for the members 20, said ways being widely spaced to receive each member at opposite edges thereof. This provides an extremely long bearing for each side member, thereby so reducing spring action as to maintain the dies practically from relative lateral movement and so substantially prevent wear of the dies from such cause. The ribs 14 on the main frame project into grooves 25 on the inner surfaces of the side members 20 to act as guides for said side members. Tapered gibbs 26 may be inserted between the side members 20 and the guide ribs 14 as a means for taking up wear. Guides 27 having lips overlapping the side members 20 to hold them against the frame are secured to the sides of the main frame and form grooves within which the side members move vertically when in operation.

Reciprocating movement is imparted to the sliding frame, and hence to the movable die, by means of a toggle connection, in the specific structure herein shown the tie beam 22 having a pillow block 28 on its upper side with a recess 29 in said block, the edges of opposite sides of said recess having bearing notches that receive a pin 30 extending from opposite sides of a link 31 comprising one member of said toggle connection. This link is pivotally attached to one end of a lever 32 having a slot 33 that receives an actuating block 34 mounted for reciprocating movement in said slot. Said block is engaged with a crank 35 formed on the driving shaft 15 within the chamber 11. The outer end of the lever 32 has a pin 36 seated in bearing notches in the edges of opposite sides of a recess 37 in a thrust block 38 secured to the under side of the bed or table 12 and as shown in Figure 2 of the drawings. This construction provides for the application of lateral force to the side members of the sliding frame to a minimum degree and thereby reduces relative lateral movement of the dies, influenced by such force, to a negligible quantity.

Springs 39 are seated in recesses in the bottom of the chamber 11, said springs being located on opposite sides of the beam 22 and thrusting at their upper ends against overhanging lips 40 projecting from opposite sides of said beam, and as shown in dotted lines in Figure 2 of the drawings. It will be noted that the constant pressure of the springs 39 not only maintains the pins 30 and 36 seated in their bearings, but, further, that said springs act to lift the sliding frame and the movable die under control of the lever 32 and the actuating block 34. The tension of these springs is preferably such as to counterbalance the weight of the sliding frame so that substantially the same force will be required to move said frame in both directions vertically.

It may further be noted that by the ar-

rangement of the mechanism for imparting reciprocating movement to the sliding frame I obtain two complete reciprocating movements thereof, and hence of the dies, in each rotation of the crank shaft, and this is a material feature of my invention, as the speed of operation of the machine may be materially increased without increasing the rate of rotation of the crank shaft.

In that form of the device shown in Figure 7 the toggle arrangement is the same as hereinabove described with the exception that the toggle members 41 and 42 are substantially of the same length. A crank rod 43 is attached to the knee joint of the toggle members at one end and its opposite end is attached to a crank pin projecting from a crank disc 44 secured to the shaft 15.

In accordance with the provisions of the patent statutes I have described the principles of operation of my invention, together with the device which I now consider to represent the best embodiment thereof; but I desire to have it understood that the device shown is only illustrative, and that the invention may be carried out by other means and applied to uses other than those above set out.

I claim:

1. A dieing machine including an upright main frame composed of two sides located at opposite sides of the machine, a reciprocating frame including side members located on opposite sides of the main frame and in sliding contact with the outer surfaces thereof at opposite sides of the machine, a tie beam secured to and connecting the lower ends of said members and a head connecting the upper ends of said members above the main frame, said tie beam extending through the opposite sides of main frame, and driving mechanism connected with said reciprocating frame for imparting reciprocating movement thereto.

2. A dieing machine including an upright main frame composed of two sides located at opposite sides of the machine, guideways formed on the outer opposite sides of the main frame at opposite sides of the machine, a reciprocating frame including side members of material width located in said guideways, a tie beam extending through the sides of the main frame and secured at its ends to the lower ends of said members and a die-supporting head connecting the upper ends of said members above the main frame, and driving mechanism connected with said reciprocating frame for imparting reciprocating movement thereto.

3. A dieing machine including an upright main frame composed of two sides located at opposite sides of the machine, a driving shaft extending within said main frame, a reciprocating frame including side members located on opposite sides of the main frame

and in sliding contact with the outer surfaces thereof at opposite sides of the machine, a tie beam secured to and connecting the lower ends of said members, and a cross-head connecting the upper ends of said members above the main frame, and a driving connection between said driving shaft and tie beam within the main frame.

4. A dieing machine including an upright main frame composed of two sides located at opposite sides of the machine, a reciprocating frame including side members of substantial width supported in sliding contact with opposite sides of the main frame at opposite sides of the machine and projecting beyond the upper surfaces thereof, a tie beam extending within the main frame and secured at its opposite ends to said side members and a cross-head connecting said side members above the main frame, a driving shaft extending within the main frame, and a driving connection between said tie beam and said driving shaft.

5. A dieing machine including an upright main frame of box-like form and composed of oppositely arranged parallel sides located at opposite sides of the machine and a die-supporting bed at the top thereof, slideways formed on the outer surfaces of said sides at opposite sides of the machine, a reciprocating frame including side members located in said slideways, a tie beam extending through the main frame and secured to the ends of said side members and a cross-head connecting the upper ends of said side members above said bed, a crank shaft extending through said main frame and supported in the sides thereof, and a driving connection between said shaft and said tie beam.

6. A dieing machine including an upright main frame of box-like form with a die-supporting bed at the top thereof, guideways formed on the outer surfaces of opposite sides of said main frame at opposite sides of the machine, a reciprocating frame including side members of substantial width located in said guideways, a tie beam extending through opposite sides of the main frame and connecting the lower ends of said side members and a cross-head connecting the upper ends of said side members, a driving shaft extending through a side member of the reciprocating frame to the interior of the main frame, and a driving connection between said shaft and said tie beam for imparting reciprocating movement to said reciprocating frame.

7. A dieing machine including an upright main frame with guideways on the opposite outer sides thereof and with oppositely arranged enlarged openings in said sides, a reciprocating frame including side members supported in said guideways, a cross-head connecting the upper ends of said side mem-

bers and a tie beam extending across the main frame through said openings therein and secured to the lower ends of said side members, a crank shaft extending through the opposite sides of said main frame and supported thereby, said shaft also extending through said side members, and an operative driving connection between said crank shaft and said tie beam for imparting reciprocating movement to said reciprocating frame.

8. A dieing machine including an upright main frame with a die-supporting bed on the upper end thereof, a reciprocating frame including side members supported in sliding contact with opposite sides of the main frame and extending above the top thereof, a tie bar connecting the lower ends of said side members and a cross-head connecting the upper ends thereof, and with extensions formed on the opposite edges of each of said side members and spaced apart thereon, said cross head being secured upon said extensions, and means for imparting reciprocating movement to said reciprocating frame.

9. A dieing machine including a main supporting frame, die supporting members mounted on said frame in cooperative relation one to the other, die operating means for imparting reciprocating movement to one of said supporting members, said operating means including a toggle joint comprising two members pivotally connected to form a knuckle, and a rotating driving member operatively engaged in sliding contact with one of said toggle members to impart swinging movement thereto.

10. A dieing machine including a main supporting frame, die supporting members mounted in cooperative relation on said frame, die operating means including two toggle members pivotally connected, one of said members being attached to a stationary support and the other of said members being operatively connected to a movable die supporting member, and a rotating driving member operatively engaged in sliding contact with one of said toggle members for imparting reciprocating movement thereto.

11. A dieing machine including a main supporting frame, die supporting members mounted on said frame in cooperative relation one to the other, die operating means for imparting reciprocating movement to one of said supports, said operating means including a toggle joint comprising two members pivotally connected to form a knuckle, one of said members having a slot therein, and a driving member comprising a crank engaged within said slot to impart swinging movement to said toggle joint and to effect relative movement of said driving member and toggle members lengthwise of said slot.

12. A dieing machine including a main

supporting frame, die supporting members mounted on said frame in cooperative relation one to the other, die operating means for imparting reciprocating movement to one of said supporting members, said operating means including a toggle joint comprising two members pivotally connected to form a knuckle, said members being of unequal length, the longer member having an opening therein, and a driving member operatively connected within said opening to impart swinging movement to said toggle.

13. A dieing machine including a main supporting frame, die supporting members

mounted on said frame in cooperative relation one to the other, die operating means for imparting reciprocating movement to one of said supporting members, said operating means including a toggle joint comprising two members pivotally connected to form a knuckle, one of said members having an opening therein, an actuating block slidably mounted in said opening, and a driving member comprising a crank engaged within an opening in said sliding block to impart swinging movement to said toggle.
